UNITED STATES PATENT OFFICE

EMIL M. ERLANDSON, OF LOS ANGELES, CALIFORNIA

WEDGE COUPLED JOINT

Application filed November 14, 1930. Serial No. 495,659.

In this specification and the accompanying drawings, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to improvements in couplings, and particularly to means for making wedge-coupled joints between longitudinally abutted members, such as drilling bit cutters and their body members. Among the principal objects of the invention are; first, to provide improved means for coupling longitudinally abutted members in such a manner as to maintain their abutting faces in compression at all times, without resorting to the use of screw-threads for accomplishing such compression; second, to furnish improved facilities for drawing the abutting faces of longitudinally positioned members into very close contact under compression by means of force applied by hammer blows; third, to secure improved means for tightening wedges in so-called wedge and pin joints, and for thereafter maintaining them in their tightened position; and, fourth, to accomplish the above objects, and others that will appear below, by means of simple and relatively inexpensive construction.

My objects are attained in the manner illustrated in the accompanying drawings, in which;—

Figure 1 is an elevation of two longitudinally abutted members, coupled together by my improved means;

Figure 2 is a partial sectional elevation of the above construction, taken on the line 2—2 of Fig. 1;

Figure 3 is an elevation of two longitudinally abutted members, coupled together by means of a different specific type of my invention;

Figure 4 is a partial sectional elevation of the construction shown in Fig. 3, the section

being taken on the line 4—4 of the last said figure;

Figure 5 is an isometric view of the special form of screw plug that I employ for positioning and locking the wedge;

Figure 6 is a front elevation of a preferred form of spring-wire clip that I employ in co-operation with the plug shown in Fig. 5; and,

Figure 7 is a perspective view of the wrench that I employ for tightening up the parts of my improved joint.

Similar reference numerals refer to similar parts throughout the several views.

My invention is particularly applicable to such uses as the positioning of end-cutting elements upon earth drilling bit bodies, and I have selected this application for the purpose of illustrating and describing it.

In the drawings I have shown a pair of longitudinally abutted, joined members 11 and 12. Of these, the member 11 may be considered for example as being the body of an earth drilling bit, and the member 12 as the upper end of a removable cutting element thereof.

In any form of my invention, one of the joined elements is provided with an axially extending pin 13. The other cooperating member is provided with an axial bore 14, into which said axial pin may be inserted snugly. The abutting faces of the pairs of members are accurately turned perpendicularly to the axis of pin 13, so as to adapt them to seat upon each other, as indicated at 15 in Figs. 1 and 3.

Pin 13 is provided with a longitudinal slot therethrough, the surface of the other end of the slot being perpendicular to the axis, as indicated at 16, and the surface of the inner end of the slot being sloped with respect to the axis, as indicated at 17. Corresponding slots are formed through body members 11, adapted to cooperate with the slots through the pins, to enable a wedge 18 to be inserted therethrough, and be driven home for tightening up the joint between the abutting members.

Thus the slots in the body members are entirely similar to the slots in the pins, but the former slots are longitudinally displaced with respect to the latter slots, to enable wedges 18 to perform their intended functions. Slot

surfaces 19 and 20 in the drawings are above slot surface 16 of the pin; and slot surface 17 of the pin is below slot surfaces 21 and 22 of the body members. Thus, in the drawings, 5 when wedges 18 are driven home, the cutting elements will be pulled tightly upwardly against the corresponding body members, so as to effect a very tight joint at 15.

It usually is desirable to provide some form 10 or radial key on one of the pair of abutting members, such as keys 23 on cutting elements 12. These keys, of course, are adapted to snugly fit the sides of a radial slot 24 in the co-operating member of the abutting pair.

15 The above described construction provides a well known and perfectly satisfactory joint for longitudinally abutted members, so long as the wedges 18 are kept tightly driven home. Torsional stresses are prevented from being 20 imposed upon the wedges by means of keys 23 and their cooperating slots 24, and the construction thus prevents any angular or longitudinal displacement between the cooperating abutting members.

25 In certain uses, such as in earth drilling, where shocks and vibrations due to operation are very great, it has been found to be very difficult or practically impossible to keep wedges 18 tightly driven home, unless special 30 means are provided for this purpose. It is with these special means that the present invention has to do. I have devised a method whereby the wedges may be very tightly driven home in the first instance, and then be 35 prevented from becoming loose in operation. Such devices as simple set-screws, follow-up plugs screwed against the outer ends of the wedges, and similar devices, are inadequate. They invariably work loose in time, and thus 40 fail to perform their functions.

Passing to a detailed description of my invention, I have found that a follow-up plug over the outer end of the wedge is effective to maintain a tight joint between longitudinally 45 abutted wedge-coupled members, only if the plug itself is positively prevented from becoming unscrewed, and only if the wedge tightening means are independent of the plug 50 tightening means. That is to say, it appears to be impossible to secure and maintain a perfectly tight joint of this kind, if only the plug itself is depended upon for tightening the wedges. To secure the best possible results, it appears to be necessary to have the plug 55 tightening means cooperate with the wedge tightening means, but the latter should in a measure be independent of the former. The two elements should be tightened concurrently, but not one by means of the other.

60 In my joint I provide a special form of follow-up plug 25, over the head of wedge 18. This plug is adapted to be screwed tightly against the head of the wedge by means of screw threads 26 in a tapped hole 65 in the body member, through which hole the

wedge is inserted. This plug has cross-slots 27 therethrough, at right angles to each other. The edges 28, formed by the intersection of these cross slots, are intermediatey intercepted by means of a circular groove 29 turned or milled in the body of the plug. The plug may be directly inserted in a hole tapped within the body member, as shown in Fig. 4, or it may be inserted in a tapped bushing 30 that is inserted within a bore in the body of the holder, and welded therein as by the circular weld 31, shown in Figs. 1 and 2. The latter construction is often preferable in severe service, since it permits of burning out the 80 bushing, and of replacing it with a new one, with a minimum of time and expense.

In any form of my invention, the wedge 18 is first driven home as tightly as possible. Plug 25 is then inserted, and tightened up against the head of the wedge by means of a special wrench, such as is indicated in Fig. 7. The working portion of this wrench is of a cross-section that adapts it to be inserted through either one of the 90 cross-slots 27. Its working end 32 is thus adapted to contact with the head of wedge 18, and the wedge may be further driven home by using the wrench as a dolly bar and applying hammer blows upon its outer end 95 33. To effect the greatest possible insertion of wedge 18, the method is to first drive the wedge home by means of hammer blows upon its head, then plug 27 is inserted and screwed home against the end of the wedge 100 by means of the wrench. Finally additional hammer blows are applied to end 33 of the wrench while a strong torsional force is being maintained upon it by means of its handle 34. In this way the plug may be 105 tightened to the utmost extent, and at the same time that the wedge is being driven home. The plug will thus be made to not only follow-up all movements of the wedge, but will be made to actually follow-up the 110 compression of the material of the wedge that is caused by the hammer blows.

When the wedge has been tightened, and plug 25 has been screwed home thereagainst in the manner described, it still is necessary 115 to insure the plug against any unscrewing. There are several means of accomplishing this, of which two are illustrated. One method indicated in Figs. 1 and 2 is to tap a hole into the outer end of wedge 18, tighten plug 25 until one of its cross slots are opposite said hole, and then screw into said hole a fillister-headed screw 35, the diameter of the fillister-head being nearly the same as the width of cross-slots 27. In this way, 125 the plug cannot become unscrewed so long as screw 35 remains in place. In practice I have found that, no matter how tightly screw 35 is originally inserted, it will eventually become loosened and drop out in very 130

severe services, such as is required of earth drilling tools. I therefore employ a fillister-headed screw having deep cross-slots 36 in its head. I then snap into place the clip 5 shown in Fig. 6, within circular groove 29 of the plug, and within one of the cross slots of the fillister-headed screw. This clip is made of spring wire centrally doubled back on itself to form a key-head 37, adapted for 10 being inserted within one of the slots of the fillister-headed screw. The legs 38 of the clip are so shaped as to adapt them to be sprung into circular groove 29. All of this construction is indicated in Figs. 1 and 2. 15 The spring clip prevents screw 35 from backing out, and therefore prevents plug 25 from becoming unscrewed.

An alternative form of locking the plug 25 is illustrated in Figs. 3 and 4. Although 20 it has been found that a screw 35, when inserted in the head of the wedge, will inevitably become loosened by shocks and vibrations under adverse service conditions, this does not appear to be the case of a screw 39 25 that is inserted directly into the body member into which the wedge is driven. Therefore it is possible to provide a washer 40 having a tongue 41 laterally extending therefrom, the tongue being given the S- 30 shape indicated in Fig. 4, and this washer being held in place by means of screw 39. The end of tongue 41 is of a width that closely corresponds to the width of cross-slots 27 and is bent into one of these slots 35 as indicated in Fig. 4.

Other means for effectually preventing plug 25 from becoming unscrewed in service will occur to those familiar with the art involved, and such means are contemplated by me.

I claim as my invention:

1. A device of the character described, comprising; abutting members joined by means of a wedge inserted through a tapped 45 hole in one of said members; and a plug screwed into said hole against the head of said wedge; said plug having an opening therethrough into which a tool may be inserted and whereby the wedge may be further driven and the plug be simultaneously tightened.

2. A device of the character described, comprising; abutting members joined by means of a wedge inserted through a tapped 55 hole in one of said members; and a plug screwed into said hole against the head of said wedge; said plug being perforate and thus affording means for engagement by a tool that is adapted for simultaneously tightening the plug while acting as a dolly-bar for further driving of the wedge.

3. A device of the character described, comprising; abutting members joined by means of a wedge inserted through a tapped 60 hole in one of said members; and a plug

screwed into said hole against the head of said wedge; said plug having cross-slots therethrough wherein a bar may be inserted for tightening the plug and for simultaneously acting as a dolly-bar for further driving of the wedge.

4. A device of the character described, comprising; abutting members joined by means of a wedge inserted through a tapped hole in one of said members; and a plug 75 screwed into said hole against the head of said wedge; said plug being perforate and adapted thereby for permitting a tool to pass therethrough for further driving of the wedge, wherein said tapped hole is formed in a bushing, and wherein the bushing is inserted in a correspondingly dimensioned hole in one of said joined members and welded in place therein.

5. The construction set forth in claim 3 in combination with a locking member that 80 engages said wedge and the walls of one of said slots, and thus prevents the unintentional unscrewing of said plug.

6. The construction set forth in claim 3 in combination with a screw tapped into the head of said wedge and extending into one of said slots, whereby the unintentional unscrewing of said plug is prevented.

7. The construction set forth in claim 3 in combination with a screw tapped into the head of said wedge and extending into one of said slots, whereby the unintentional unscrewing of said plug is prevented; and means carried by said plug for preventing 95 the unintentional unscrewing of said screw.

8. The construction set forth in claim 3 in combination with means carried by one of said joined members and engaging a wall of one of said slots and adapted thereby to prevent the unintentional unscrewing of said plug.
